FRAME FOR SECURING DISPLAY
WINDOWPANES

Walter Hallauer, Schaffhausen, Switzerland

Application June 14, 1949, Serial No. 98,972
In Switzerland June 19, 1948

3 Claims. (Cl. 189—78)

1

The present invention relates to a frame for securing display-window panes in which frame a grooved spring strip or sections of such a strip are provided for the purpose of clamping and holding at least one frame cover strip. In known constructions of this type the spring strip is screwed to the supporting frame, and the cover frame, which is provided with a tongue, is clamped between the spring strip and the supporting frame. In the constructions in which the window frame is cemented in, the entire cavity of the cover frame or cover frames has to be filled with cement, this representing not only a troublesome piece of work but also an unnecessary consumption of cement, quite apart from the fact that in spite of the comparatively large quantity of cement used there is no guarantee that the cavity is completely filled and that the glass pane actually is firmly embedded in the cement.

Those constructions which are intended to permit of the securing of the glass pane without the use of cement and in which a cover frame is provided on one side only exhibit the drawback that the spring strip must be screwed to the supporting frame at an exact distance from the supporting frame, said distance corresponding to the thickness of the glass pane, and this renders difficult the performing of any preliminary work on the supporting frame strips on a repetition basis.

The purpose of the present invention is to overcome these drawbacks by suitable shaping of the spring strip and the cover strips or of the means of securing the spring strip. The invention consists in the fact that the spring strip possesses, in addition to the groove serving for the securing of a cover strip, a number of parallel grooves which so correspond to grooves of a rail serving for the clamping of said spring strip to the supporting frame that said grooves may be laterally displaced in relation to each other by at least the distance between two adjacent grooves, and also in the fact that the cover strips used are provided with tongues which limit the cement cavity to minimum cement requirements and prevent access of the cement to the spring strip. A rail of rectangular cross-section may be used as the grooved rail for clamping the spring strip to the supporting frame. A cover strip may also, however, be provided with grooves and serve to clamp the spring strip to the supporting frame.

In the drawings,

Figure 1 is a section through a prior art frame provided with a spring strip;

Figure 2 is a section through another prior art frame provided with a spring strip;

2

Figure 3 is a section through a frame provided with a spring strip constructed in accordance with the principles of the present invention;

Figures 4, 5, and 6 are all sections through different embodiments of the present invention.

In Figs. 1 and 2, spring strips 2 and 3 respectively, provided with a groove 4, is secured by screws 5 to the supporting frame 1. Instead of a continuous strip, it is also possible to screw sections only of such a strip on to the supporting frame. The two cover channels 6 and 7 and the cover channel 8 (Fig. 2) are clamped under the spring strips 2 and 3 respectively. In order to secure the glass pane S, the entire cavity of the cover channel must be filled with cement. The spring strip 9 (Fig. 3) in accordance with the invention is provided both with the groove 10 for securing the cover strip 12 and with grooves 13 which correspond to grooves 14 in the cover strip 15. Together with the cover strip 15, the spring strip 9 is screwed by means of screws 17 to the supporting frame 16, so that not only the spring strip but also the cover strip is rigidly secured to the supporting frame 16, so that they cannot be knocked loose in windows and doors. The tongue 12a of the cover strip 12 is inserted and clamped below the groove 10 of the spring strip. If a greater distance proves necessary between the two cover strips or rails 15 and 12, either through widening of the aperture for the glass pane on account of an increase in the thickness of the glass pane 18 or because of the supporting frame 16 being covered with light-alloy sheets 26, the spring strip 9 may be displaced by the distance between two adjacent grooves, as shown in Fig. 4. The two cover strips 12 and 15 are provided with overlapping tongues 19 and 20 which, even when the distance between the cover strips is increased, still seal off the cement cavity from the adjacent cavity of the rail 12 and prevent cement from coming into contact with the sheet steel springs, thus preventing any corrosion of the latter by the cement.

Fig. 5 illustrates a further embodiment. The spring strip 21 is screwed with a grooved strip 12b to the supporting frame 22 and the tongue 23 of the two-sided cover frame 24 is clamped below the projecting part of the edge. Said cover frame 14a is provided with ledges 25 which seal off the cement cavity from the hollow cavity of the cover frame. By means of springs 27 slipped on to the binding piece 25a, the strength of the connection between the cover frame 24 and the supporting frame 22 may be increased.

Fig. 6 shows the same embodiment with a one-sided cover frame.

I claim:

1. A frame for securing display window panes, comprising in combination with a supporting frame and hollow cover strip means engaging said supporting frame; a spring strip connected with said supporting frame and comprising one portion having a plurality of parallel ridges and grooves formed therein, another portion having a tongue, and an intermediate portion located between the two first-mentioned portions, said cover strip means comprising a portion having a plurality of parallel grooves and ridges in engagement with the ridges and grooves of the first-mentioned spring strip portion, another portion having a tongue extending under the tongue of the second-mentioned spring strip portion and an inner member separating the interior of said hollow cover strip means into two chambers, one of said chambers being adapted to be filled with cement, the other one of said chambers containing a portion of said spring clip.

2. A frame for securing display window panes, comprising in combination with a supporting frame and two hollow cover strips engaging said supporting frame; a spring strip comprising one portion having a plurality of parallel ridges and grooves formed therein, another portion having a tongue, and an intermediate portion located between the two first-mentioned portions and firmly connected to said supporting frame, one of said cover strips comprising a portion having a plurality of parallel grooves and ridges in engagement with the ridges and grooves of the first-mentioned spring strip portion, the other cover strip having a tongue extending under the tongue of the second-mentioned spring strip portion, said two cover strips enclosing a hollow interior and having cooperating tongues separating said interior into two chambers, one of said chambers

being adapted to be filled with cement, the other one of said chambers containing a portion of said spring clip.

3. A frame for securing display window panes, comprising in combination with a supporting frame and hollow cover strip means engaging said supporting frame; a spring strip connected with said supporting frame and comprising one portion having a plurality of parallel ridges and grooves formed therein, another portion having a tongue, and an intermediate portion located between the two first-mentioned portions, said cover strip means comprising a rail having a plurality of parallel grooves and ridges in engagement with the ridges and grooves of the first-mentioned spring strip portion, and a cover strip having a tongue extending under the tongue of the second-mentioned spring strip portion, and another tongue separating the interior of said hollow cover strip means into two chambers, one of said chambers being adapted to be filled with cement, the other one of said chambers containing a portion of said spring clip.
